UNITED STATES PATENT OFFICE.

HORACE A. PALMER, OF ERIE, PENNSYLVANIA.

DESIGN FOR A SEWER-GRADE.

SPECIFICATION forming part of Design No. 19,636, dated February 4, 1890.

Application filed August 9, 1889. Serial No. 320,285. Term of patent 14 years.

To all whom it may concern:

Be it known that I, HORACE A. PALMER, a citizen of the United States, residing at Erie, in the county of Erie, State of Pennsylvania, have invented or produced a new and original Design for Sewer-Grating, of which the following is a full, clear, and exact specification.

The object of this design is to provide a novel sewer-grating; and the leading features thereof consist in an annular band having radial outwardly-projecting arms, and parallel bars within the space surrounded by the band, which bars are chords of the circle formed by the latter, said band, arms, and bars having their top surfaces each provided with a series of separated projecting points.

The design is exhibited by the accompanying drawing, in which the figure is a perspective view of the sewer-grating.

In the drawing, the numeral 1 indicates the

annular band; 2, the radial outwardly-projecting arms; 3, the parallel bars arranged within the space surrounded by the band, and which are chords of the circle formed by the band; 4, the annular row of separated 25 projecting points on the top surface of the band; 5, the separated projecting points on the top surfaces of the parallel bars, and 6 the separated projecting points on the top surface of the radial arms. 30

What I claim is—

The design for a sewer-grating, substantially as shown and described.

In testimony whereof I affix my signature in presence of two witnesses.

HORACE A. PALMER.
